UNITED STATES PATENT OFFICE.

ELIAS W. TUCKER AND ASBURY P. ORR, OF ARCADIA, INDIANA.

CLOTHES-POUNDER.

SPECIFICATION forming part of Letters Patent No. 404,234, dated May 28, 1889.

Application filed January 26, 1889. Serial No. 297,743. (No model.)

To all whom it may concern:

Be it known that we, ELIAS W. TUCKER and ASBURY P. ORR, citizens of the United States, residing at Arcadia, in the county of Hamilton and State of Indiana, have invented certain new and useful Improvements in Washing-Machines, of which the following is a specification, reference being had therein to the accompanying drawings.

10 Our invention relates to an improvement in washing-machines; and it consists in the construction and arrangement of parts hereinafter described and claimed.

The object of our invention is to provide a 15 pounder for washing clothes which will be simple and efficient in its working and cheaply manufactured. We attain this object by the construction illustrated in the accompanying drawings, wherein like letters of reference indicate 20 corresponding parts in the several views, and in which—

Figure 1 is a perspective view. Fig. 2 is a vertical section taken through the center of the pounder, and Fig. 3 is a bottom view. 25 Fig. 4 is a sectional view taken through the line $x x$ of Fig. 3.

In washing-pounders of this class heretofore made it has generally been customary to construct the valve over the mouth of the 30 tubes with a metallic spring, or to place a flexible strip of leather or other material over the opening, one end only being attached. In these cases there has been experienced more or less annoyance and trouble, inasmuch as 35 they soon become disarranged and thereby render the pounder inoperative, and owing to the peculiarity of their construction they cannot be readily replaced or repaired. To overcome these objections and still provide a 40 complete and perfect working device is the aim of this invention.

In the drawings, A represents the body of the pounder, preferably of metal of conical shape, through the apex of which is extended 45 a cylindrical tube, B, in which is adapted to be placed the handle. This tube is secured rigidly to the body. Horizontally disposed in or near the center of the cone or body is a plate, C, its edges being placed in a groove, 50 a , made in the walls of the cone, the edges of the plate being brazed or soldered therein.

Leading from points on the outside of the cone, on opposite sides of the tube B, are air-tubes D, which incline downwardly toward each other through the walls of the cone, their 55 lower ends meeting and entering an opening, c , in the center of the plate C. These tubes are rigidly secured in place, their inner faces at the lower ends extending laterally across the opening, the remaining portions being secured to the edges of the opening. The ends of the tubes thus occupy the space formed for the opening. Adjacent to the ends of the opening c are arranged clasps E, which are formed of single pieces of spring metal having 60 their ends made fast to the under face of the plate C and their central portions slightly raised. The inner edges of these clasps are indented or depressed, whereby the normal position of this part is near the plate, but 70 owing to the resiliency of the metal can be raised by the insertion of a wedge or similar implement between the clasp and plate. These clasps are of greater length than the width of the opening c . 75

F represents a rubber strip, diaphragm, or valve formed of a straight rectangular strip of vulcanized rubber, the width of which is greater than the width of the opening c , over which it is placed. The ends of this rubber 80 valve are placed in the clasps E, it being stretched tightly over the opening. The ends do not occupy the entire space within the clasp, it being narrower, thereby allowing room for the insertion of an implement to 85 raise the clasp and adjust the rubber.

It will be seen by the above-described construction that the air is prevented from escaping from the pounder when it is forced down, but is allowed free access when it is 90 raised, the rubber valve yielding and the air entering through the opening.

When the rubber becomes worn or stretched, it can be readily replaced by another, or adjusted in a few moments by raising the depressed part of the clasps and freeing the 95 ends.

I am aware that many minor changes in the construction and arrangement of the parts of our device can be made without in the least 100 departing from the nature and principle of our invention.

Having thus described our invention, what we claim as new, and desire to secure by Letters Patent, is—

The washing-pounder herein described, consisting of the conical body A, the cylindrical handle-tube B, the horizontally-disposed plate C, having a central opening, c, the air-tubes D, entering said opening and extending to the outside of the cone, the clasps E, formed of strips of spring metal having depressed

inner edges, and the flexible valve having its ends secured in the clasps, substantially as described.

In testimony whereof we affix our signatures in presence of two witnesses.

ELIAS W. TUCKER.
ASBURY P. ORR.
